UNITED STATES PATENT OFFICE.

DAVID SAMIRAN, OF Langley Field, Virginia, assignor of one-half to
PHILLIPS MELVILLE, OF Langley Field, Hampton, Virginia.

FLUID SEGREGATOR.

Application filed September 28, 1927. Serial No. 222,619.

This invention relates to a device for the automatic isolation of fluids, but more particularly to a device for straining and separating water and sediment from gasoline. 5 The invention is applicable for the separation or isolation of any two fluids of different specific gravities which are non-miscuous, such as oil and water.

The invention has for its object to provide 10 certain material improvements in the art such as the adjustability of the float to any desired degree of buoyancy to adapt the device for use in the separation and isolation of various fluids which differ in specific 15 gravity.

A further object of the invention is to provide means for obviating the effect of vibration between the float and the needle valve so that the device will properly function under the usual conditions of service. 20

With these and other objects in view, the invention consists of the construction, arrangement and combinations of parts, all of which will be first fully described and afterwards specifically pointed out in the appended claims. 25

Referring to the accompanying drawings:

Fig. 1 is a side elevation of the device;

Fig. 2 is a vertical sectional view of the 30 same;

Fig. 3 is a diagrammatic sectional view illustrating the location of the component parts.

Fig. 4 is a similar view illustrating the 35 action of the deflector and the direction of flow of the lighter and heavier fluids within the device;

Fig. 5 is a similar view illustrating the 40 buoyancy level of the float raised and the needle valve in position for discharging a quantity of the heavier fluid.

Fig. 6 is a similar view illustrating the 45 buoyancy level restored and the needle valve returned into normal position after discharging the heavier fluid.

Like numerals of reference indicate the same parts throughout in order to illustrate the parts.

1 indicates the isolator or separator, which 50 includes the top casting 2 having therein the large cored inlet passage 3 forming the deflector 4, and the relatively small circulating passage 5 with which the outlet passage 6' connects. This outlet passage 6' is shown 55 in Fig. 2 as containing a threaded plug. This

plug is removed and a pipe or tube (not shown) is connected to said passage and leads to a carburetter or the like.

7 indicates the float chamber which may be of any suitable material, but which is 60 shown of glass in the accompanying drawings. This chamber is conventionally shaped and has its upper edge slightly flared at 8 to be received by the clamping ring 9 against a suitable packing gasket 10, disposed under 65 the flange 11 of the top casting. This assembly is effected by the screws 12 as shown in Figures 1 and 2.

The bottom 13 of the float chamber is apertured to receive the upstanding tubular valve-stem guide 14, which as shown in Figure 2, is provided with a threaded nipple-end 15 which is passed through the bottom 13 of the float chamber, said threaded end of the said guide also including a flange 16 under which 70 is disposed a suitable packing gasket 17 to effect a fluid tight joint.

The said threaded end of the said guide is internally threaded to receive the centrally bored valve seat 18. Inclosing the threaded 80 nipple-end 15, is a retaining nut 19 acting against a suitable packing gasket 20 by means of which retaining nut 19 this assembly is effected. Threaded in the bottom of said retaining nut 19 is a drain valve 21 which includes an upper flanged head 22 and a central bore 23, in communication with which bore is a drain port 24 through the wall of the valve 21. A wing nut 25 is secured to the bottom end of the valve 21, by means of 85 which, rotation is imparted to said valve to raise or lower the flanged head 22 and to raise and lower the drain port 24 into and out of communication with the chamber formed by the threaded nipple-end 15. 90

26 indicates a long tubular screen located in the side of the float chamber and connected, as shown in Fig. 2 to the discharge end of the deflector 4 which tubular screen receives all 95 fluids and sediment passing into the device.

27 indicates the float which is provided with a central tube 28 by means of which, said float is slidably mounted on the upstanding tubular valve-stem guide 14 heretofore described. 100

Resiliently and flexibly connected to the float 27 is the stem 29 of the needle valve 30, so that said valve is seated and unseated by the float 27, which connection is effected by the springs 31 as shown in Figs. 1 and 2. 110

Arranged in the bottom of the float is a series of stand pipes 32 of varying lengths (Fig. 2) which are arranged in pairs of the same length as shown in Fig. 2. Disposed 5 under said series of stand pipes is a washer 33 and a lock washer 34, the same being provided with one pair of perforations 35 which may be brought in position to register with any one pair of said stand pipes 32 or to cover 10 all the said stand pipes 32.

Disposed under the passage 5 leading to the outlet passage 6' is a screen 36, while at the upper end of said passage 5 is a closed-end tube 37 having a series of narrow slots 38 15 therein near the top thereof, said slotted end of the tube 37 extending upwardly within and to one side of the sieve 39 which is disposed over the inlet passage 3, while the upstanding boss 40 of the top casting 2 is threaded at 41 20 for connection with a pipe line, tank or other supplies.

Having thus described the component parts of this invention, its operation is as follows:

25 Fluid supplied to the device through a pipe or feed line tank or other supply (not shown) passes through the sieve 39 and thence into the inlet passage 3 onto the deflector 4 and into the tubular sieve 26, thence into the float chamber 7. In order to adapt the device to the isolation or separation of the particular non-miscuous fluids of different specific gravities to be handled, such as the isolation or separation of water from gasoline, the 30 buoyancy of the float 27 is adjusted as follows: The washer 33 and lock washer 34 under the float 27 are rotated until that pair of stand pipes which are of the length previously determined for water, are uncovered, 35 and the float is inverted and then immersed 40 in water and permitted to fill. The liquid enters one stand pipe and air escape through the other so that the float fills up to the inner ends of the stand pipes, but no further, 45 as the air remaining in the float is trapped in the float and precludes the further entry of water. It will thus be seen that the longer the stand pipe, the less the quantity of liquid can enter the float, so that by this means the 50 float can be exactly and accurately weighted to adjust the relative buoyancy of the float, to the end that the buoyancy level "B" is maintained at constant height, as diagrammatically illustrated in Fig. 3. When the float 55 has thus been filled, the washer 33 and lock washer 34 are again rotated to seal said stand pipes 32. The float is then reversed and assembled in position shown in the drawings.

In the diagrammatic views, the buoyancy 60 level is indicated by "B" while "C" indicates the lighter component of the liquid such as gasoline, and "D" indicates the heavier component such as water which is separated and isolated by the device.

65 In Fig. 3, the arrows indicate the uninter-

rupted flow of the lighter component such as gasoline in the absence of the heavier component, such as water.

Fig. 4, however, illustrates a quantity of the heavier component such as water entering the device and illustrates the operation of the deflector 4 which facilitates the rapid separation of the two components. The lighter components in the float chamber being displaced by the heavier component entering the float chamber, pass out through the passage 5 and into the screen 39, in proportion to the quantity of the heavier component entering the float chamber, for as the heavier component enters the device, the lighter component already therein must be displaced therefrom in the same proportion. Such flow of the liquid will continue by reason of the relative diameters of the inlet passage 3 and the passage 5, as long as the heavier component 75 continues to enter the float chamber. I have found by experiment that in the absence of such an arrangement for permitting displacement of the lighter component from the device as by the provision of passages 3 and 5, the sudden introduction of a large quantity of the heavier component would tend to accumulate in the inlet passage by reason of the upward pressure of the lighter component within the float chamber, unless the inlet neck is of diameter equal to that of the float chamber. Such latter construction however is unwieldy and undesirable. In order to overcome the disadvantage of a lodgment of a large quantity of the heavier component in 90 the inlet passage 3 of the device, when a large quantity of the heavier component is suddenly introduced into the device, the circulating passage 5 is provided which permits and allows the displacement of the lighter 95 component from the float chamber into the feed line and at a point above the inlet passage 3. This prevents and overcomes the tendency of a suddenly introduced large quantity of the heavier component to lodge in the 100 inlet passage 3, by permitting such heavier component to pass into the float chamber. The action is somewhat analogous to that of a venting action, in that it provides for the displacement from the float chamber of a 105 lighter component sufficient to permit the entrance of the heavier component therein, since a quantity of the heavier component cannot be suddenly introduced 110 into the float chamber unless an equal volume 115 of the lighter component is displaced therefrom to provide for the entrance of the heavier component. The circulating passage 120 5 is provided to assist in the necessary displacement of the lighter component from the float chamber upon the sudden introduction 125 therein of a large quantity of the heavier component.

While the incoming fluid may enter the circulating pipe 5 in very small quantity, the 130

small narrow slots 38 in the upstanding pipe 37, prevent the entrance of sediment into the same, while the fluid must also pass through the screen 39 before it can enter the small narrow slots 38.

When a sufficient quantity of the heavier component enters the float chamber, it causes a rise in the buoyancy level B, as from dotted lines in Fig. 5 to full lines in said figure. By reason of the relative buoyancy, the float is displaced upwardly as shown in said figure which raises the needle-valve 30 and permits the escape of the heavier component through the drain 23. This discharge continues until the buoyancy level B is restored, at which level the float has descended into position to reseat the needle-valve 30 and shut off further evacuation of the heavier component as shown in Fig. 6. This action is automatically repeated each time the quantity of the heavier component in the float chamber becomes sufficient to cause a rise in the buoyancy level.

Under certain conditions and particularly those existing in vehicles of all kinds, movement, tilting and vibration thereof may seriously interfere with the proper functioning of a device of this class. For this reason I prefer to mount and suspend the needle valve 39 and stem 29 as heretofore described, and thereby obviate any direct or frictional contact between the said stem and the float, while the flexible or resilient spring connection employed, permits free vertical movement of the float within the limits of the resiliency of the springs without imparting any movement to the needle-valve. By this means vibration affecting the float is absorbed by the springs without affecting the normal seated position of the needle valve.

Having thus fully described the invention, it may be obvious to those skilled in the art that the construction shown and described is subject to changes, alterations and modifications. I am fully aware of this and it is to be understood that the specific construction shown in the accompanying drawings are merely illustrative of any preferred construction, and that I consider myself clearly entitled to all such changes and modifications as fall within the limit and scope of the appended claims.

I claim:

1. A device of the character described including a float chamber, a top member therefor having an inlet, a deflector, a circulating and an outlet passage in said top member, a sieve to receive fluid from said deflector, a float within said float chamber, an upstanding valve-stem guide within said float chamber, upon which guide the said float is slidably mounted, a needle-valve and stem, the stem of said needle-valve being slidably mounted in said guide, a needle-valve seat, said float chamber being provided

with a discharge passage commanded by said needle valve, means for resiliently connecting said float with said needle-valve, and means for adjusting the buoyancy of said float, the whole arranged for the separation and isolation of fluids of different specific gravities within the float chamber. 70

2. A device of the character described including a float chamber, a top member therefor having an inlet passage, a deflector and an outlet passage in said top member, a sieve to receive fluid from said inlet passage and deflector, a float within said float chamber, an upstanding valve-stem guide within said float chamber upon which guide the said float is slidably mounted, a needle-valve and stem, the stem of said needle-valve being slidably mounted in said guide, a needle-valve seat, said float chamber being provided with a discharge passage commanded by said needle-valve, means for resiliently connecting said float with said needle-valve, and means for adjusting the buoyancy of said float, the whole arranged for the separation and isolation of fluids of different specific gravities 80 within the float chamber. 85

3. A device of the character described including a float chamber, a top member therefor having an inlet, a deflector, a circulating and an outlet passage in said top member, a sieve to receive fluid from said deflector, a float within said float chamber, an upstanding valve-stem guide within said float chamber upon which guide the said float is slidably mounted, a needle-valve and stem, the stem of said needle-valve being slidably mounted in said guide, a needle-valve seat, said float chamber being provided with a discharge passage commanded by said needle-valve, and means for resiliently connecting 90 said float with said needle-valve, the whole arranged for the separation and isolation of fluids of different specific gravities within the float chamber. 95

4. A device of the character described including a float chamber, a top member therefor having an inlet passage, a deflector and an outlet passage in said top member, a sieve to receive fluid from said inlet passage and deflector, a float within said float chamber, an upstanding valve stem guide within said float chamber upon which guide the said float is slidably mounted, a needle-valve and stem, the stem of said needle-valve being slidably mounted in said guide, a needle-valve seat, said float chamber being provided with a discharge passage commanded by said needle-valve, and means for resiliently connecting said float with said needle-valve, the whole arranged for the separation and isolation of fluids of different specific gravities 100 within the float chamber. 105

5. A device of the character described including a float chamber, a top member therefor having an inlet, a deflector, a circulating 110

and an outlet passage in said top member, a sieve to receive fluid from said deflector, a float within said float chamber, an upstanding valve-stem guide within said float chamber upon which guide the said float is slidably mounted, a needle-valve and stem, the stem of said needle-valve being slidably mounted in said guide, a needle-valve seat, said float chamber being provided with a 10 discharge passage commanded by said needle valve.

6. A device of the character described including a float chamber having an inlet passage for the introduction of a fluid having 15 a light and a heavy component, an outlet passage for the light component and an outlet for the heavy component, a float, a needle valve actuated by the float for commanding the outlet for the heavy component, and 20 means in addition to the outlet passage for the light component for facilitating the displacement from the float chamber of the light component within the chamber upon entrance of the heavy component therein 25 through said inlet passage.

7. A device of the character described including a float chamber, a fluid inlet and outlet, a float in said float chamber, means for adjusting the buoyancy of the float, and 30 means in addition to the fluid outlet for facilitating the displacement from the float chamber of a light component of a fluid therein upon entrance of a heavy component within the float chamber.

35 8. A device of the character described, including a float chamber, a fluid inlet and outlet, a float in said float chamber, a needle valve and stem, means for resiliently connecting the float with the needle valve and 40 stem, means for adjusting the buoyancy of the float, and means in addition to the fluid outlet for facilitating the displacement from the float chamber of a light component therein, upon entrance of a heavy component 45 within the float chamber.

9. A device of the character described including a float chamber, a top member therefor having an inlet and an outlet passage and a circulating passage providing means 50 for facilitating the displacement from the float chamber of a lighter component upon the entrance of a heavier component through said inlet passage, a float within said float

chamber, a needle valve and seat, said float chamber being provided with a discharge 55 passage commanded by said needle valve and means for resiliently connecting said float with the needle valve, the whole arranged for the separation and isolation of fluids of different specific gravities within the float 60 chamber.

10. A device of the character described including a float chamber and an inlet and an outlet passage for introducing fluid to and from the float chamber and including in addition thereto, means for facilitating the displacement from the float chamber of a lighter component upon the entrance of a heavier component through said inlet passage, a float within said float chamber, a 70 needle valve and seat, said float chamber being provided with a discharge passage commanded by said needle valve, the whole arranged for the separation and isolation of fluids of different specific gravities within the 75 float chamber.

11. A device of the character described including a float chamber, a float, a needle valve and seat and an opening commanded by the needle valve, a top member for the 80 float chamber, the same having an inlet, a deflector and a circulating and an outlet passage.

12. A device according to claim 1, in which the means for adjusting the buoyancy of the 85 float, includes a plurality of standpipes of varying lengths extending within the float from the bottom thereof.

13. A device according to claim 2, in which the means for adjusting the buoyancy 90 of the float, includes a plurality of standpipes of varying lengths extending within the float from the bottom thereof.

14. A device according to claim 1, in which the means for adjusting the buoyancy of the 95 float, includes a plurality of standpipes extending within the float from the bottom thereof.

15. A device according to claim 2, in which the means for adjusting the buoyancy of the 100 float includes a plurality of standpipes extending within the float from the bottom thereof.

In testimony whereof I affix my signature.

DAVID SAMIRAN.
